UNITED STATES PATENT OFFICE.

ACHILLE KAIS, OF HIGHLAND PARK, MICHIGAN.

BURNER.

Application filed August 23, 1923. Serial No. 659,014.

To all whom it may concern:

Be it known that I, ACHILLE KAIS, a citizen of the United States of America, and a resident of Highland Park, in the county of Wayne and State of Michigan, have invented a new and Improved Burner, of which the following is a description.

My invention relates to a liquid fuel burner and more particularly is intended as 10 an improvement on the invention forming the subject matter of an application filed by Kaiserman & Zaugg, April 15, 1921, Serial Number 461515 and is also in some respects an improvement on the invention 15 forming the subject matter of an application for patent filed by me June 22, 1923, Serial Number 647113.

The general object of the present invention is to improve burners of the type shown 20 in my aforesigned applications whereby to produce a clean effective flame well adapted for use in industrial furnaces and provide a burner efficient for use in country homes where gas or electricity is not available.

25 The nature of the present improvements and their distinctive features and advantages can best be explained in connection with a specific description of the illustrated example of the invention as hereinafter given.

30 Reference is to be had to the accompanying drawings forming a part of this specification, it being understood that the drawings are merely illustrative of one example of the invention.

35 Figure 1 is a side elevation of a burner installation embodying my invention;

Figure 2 is a plan view thereof;

Figure 3 is a longitudinal vertical section in a plane indicated by the line 3—3, Fig-

40 ure 2;

Figure 4 is a transverse vertical section as indicated by the line 4—4, Figure 3;

Figure 5 is a horizontal section as indicated by the line 5—5, Figure 3;

45 Figure 6 is a transverse vertical section as indicated by the line 6—6, Figure 3;

Figure 7 is a longitudinal vertical section on the line 7—7, Figure 2;

Figure 8 is a transverse vertical section-

taken on the line 8—8, Figure 2 and showing in elevation the oil level control tank and its valve controlling means;

Figure 9 is a transverse vertical section through the gas burner attachment as indicated by the line 9—9, Figure 10;

Figure 10 shows an end elevation of the gas burner attachment;

Figure 11 is a detail in vertical section as indicated by the line 11—11, Figure 9.

In carrying out my invention in accordance with the illustrated example a steam generator 15 is provided having a water inlet 115 and a tubular double-walled steam chamber 16 at the top, the interior of which constitutes a combustion chamber 17. The 65 assemblage comprising the steam generator 15, steam chamber or dome 16, and combustion chamber 17, is essentially that disclosed in my first-mentioned application and needs no detail explanation herein. From the 70 steam chamber 16 leads a steam outlet pipe 18 communicating by a pipe 19 (Figure 2) with a four-way cross 20, a branch of which connects by pipe 121 with a pressure gage 21. Another branch constitutes a steam outlet 75 leading through a valve 22 and a pipe 23 (Figure 2) leads the steam to an atomizer head designated generally by the numeral 24.

An oil pipe 25 leads also to the atomizer head 24 at the under side thereof, said oil 80 pipe connecting by its inlet 125 with an oil level control reservoir 26, said reservoir and its valve controlling appurtenances being disclosed in my second-mentioned application, the control means being slightly modified as hereinafter explained. The numeral 85 126 indicates an oil supply pipe leading to the reservoir 26.

A nozzle 27 is disposed in a fitting 28 mounted horizontally in the atomizer head 90 24 and communicates by a port 29 with the interior of said head and therefore with the steam pipe 23. The inlet end of the nozzle 27 is controlled by a needle valve 30. The fitting 28 is suitably held in place as by a set 95 screw 31.

Communicating with the head 24 also at a side thereof is an air pipe 32 which in

practice may be connected with a hand-operated air pump, the purpose of which will appear hereinafter.

The steam and air nozzle 27 discharges to a burner nozzle 33 at one end of the combustion chamber 17, there being provided an inclined drip pan or spout 34 at the front of said burner 33 to conduct drip oil to the interior of the chamber 17.

10 I provide a water feed control device designated generally by the numeral 36 which is formed with a diaphragm 37. A water inlet pipe 38 leads into said water feed control device 36 and a water outlet pipe 39 leads from said device 36, both the inlet and outlet being above the diaphragm 37. The outlet pipe 39 connects with the inlet pipe 115 of the steam generator 15. A water port 40 connects the inlet pipe 38 with the outlet pipe 39 and said port 40 is controlled by a check valve 41 here shown as a ball valve, said valve 41 being adapted to be engaged by a lift pin 141 on the diaphragm 37. The chamber 42 below the diaphragm 37 communicates with the steam line by a branch pipe 43 from the cross 20. If excessive steam pressure develops in the chamber 42 the steam will back up through the branch 43, cross 20, pipes 19 and 18, and the back pressure developed will result in lowering the water level in the generator 15 and cause the water to back up through the inlet 115, pipe 39, port 40 and inlet pipe 38. Thus, the pressure on the diaphragm at the water side 35 and the steam side will be so maintained that there will be a slight preponderance of pressure on the steam side of the diaphragm 37 sufficient to maintain the valve 41 open to the flow of water of the generator 15 but any 40 excessive preponderance of pressure on the steam side of the diaphragm will be balanced by the back pressure of the steam on the water circuit and therefore on the diaphragm 37. At the lower end of port 40 is valve 62 45 on the diaphragm 37 and a spring 63 at the steam side of the diaphragm presses against said valve tending to balance the pressure of the water on the diaphragm. The valve 62 has two flat sides 64 so that a movement 50 of the valve to the port 40 will not totally close said port. The valve lift pin 141 has guided movement in a socket 65 on the upper end of a vertical spindle 66 adapted to turn in the bottom of the body of the control device 36. A spring 67 is coiled about the spindle 66 to press it against a nut 68 to regulate the tension of the spring.

55 The spindle 66 may be turned to thus turn the pin 141 for regulating the inlet flow past the ball check valve 41 to start the flow of water and maintain said valve 41 open until steam pressure is sufficient to hold the valve in the open position. The nut 68 has teeth 69 and a lock spring 70 secured to the body 60 of the control device 36 has a rib 71 adapt-

ed to engage between teeth of the nut 68 to hold the nut in adjusted position.

In my second-mentioned application, Serial Number 647,113 the oil level control reservoir 26 is fully described as including a valve controlling the flow of oil into the reservoir from inlet 126. Said valve is float-controlled and is fully described in my said second application, together with means to operate the valve by a predetermined weight of oil in the drip pan 49. The present application in common with said second application includes a filter 44 and oil pressure reducing tank 45, which here need no particular description. The valve of the reservoir 26 in the present instance is indicated by the numeral 46. The numeral 47 indicates an overflow duct from the reservoir 26 to a pipe 48 discharging to drip pan 49 suspended on a lever 50 as fully described in my said second application. Said lever 50 is here shown fulcrumed at 51 on a bracket 52 on reservoir 26 and one arm of the lever has a toe 53 adapted to engage and rub over a toe 54 on a lever 55 disposed beneath a vertically movable pin 56 about which is coiled a spring 57. On spindle 57 above the reservoir 26 is a yoke 58 provided with an upstanding pin 59 to receive one end of a coupling bar 60, the opposite end 75 of which is secured by nuts 61 to the valve stem 46. Thus, upon the overflow of oil into the drip pan 49 from reservoir 26, the lever 50 will rock downwardly, and its toe 53 will engage the toe 54 of lever 55 and 80 rock said lever 55 in a manner to lift the pin 56 thereby through yoke 58 and coupling bar 60 lifting the valve 46 and closing said valve, thereby cutting off the inflow of oil to reservoir 26 as fully described in my application No. 647,113. The feature of the present invention in so far as the same relates to the reservoir 26 and its appurtenances, resides essentially in the elements 53, 54, 55 for operating the pin 56 in a direct 85 and efficient manner.

A sleeve 72 is threaded onto the valve 30 and a lever 73 has a cross head fulcrumed as at 74 on a bracket 75 appurtenant to the atomizer head 24. One arm 76 of lever 73 90 is pivoted to the sleeve 72. The lever 73 connects by a wire 77 and other suitable connections with a thermostatic device (not shown) on the furnace so that the lever will be rocked under excessive heat in the furnace 100 A, in connection with which the burner assemblage is installed. The rocking of the lever 73 will through its arm 76 cause the sleeve 72 to move the valve 30 to the closed position for cutting off the flow of steam or 105 air from port 29, thereby destroying the suction on the oil pipe 25. The second cross arm 78 on lever 73 has secured thereto one end of a connecting bar 79, the opposite end of which connects with one arm of 110

an essentially T-shaped lever 80, the other arm of which has secured thereto a valve stem 81 having a valve 82 controlling an air inlet port 83 through which air is directed 5 to an oil passage 84 leading to the burner nozzle 33 from a vacuum chamber 85 at the upper end of the oil pipe 25. The arm 78 of lever 73 also pivotally supports a lever 86 adapted to be manually operated in any 10 suitable manner, the connecting bar 79 for operating the air valve 82 is carried by the lever 86 instead of by the arm 78 of lever 73 so that said connecting bar 79 will be operated by locking of the lever 73 but may be 15 manually operated by the lever 86. The lever 86 has a hook 87 adapted to engage against the shoulder 88 on the bracket 75 to limit the movement of the arm 78 and lever 86 in one direction. A screw 89 in the 20 bracket 75 limits the movement of the hook 87 in the other direction and thus limits the movements of the levers 73 and 86.

In my present invention the steam generator is supported as follows: The tubular steam chamber 16 is provided within the combustion chamber 17 thereof with a frame 90 as best seen in Figure 4, the upper portion of which is in the form of a separate section 91. Said frame fits snugly within 25 the combustion chamber 17 against the inner wall of the steam chamber 16. The ends of the body of the frame 90 and of its separate section 91 jointly receive fastener screw bolts 92 which pass into the joint between 30 the main and separate sections and through the front of atomizer head 24. The oil drip pan 34 is integral with the frame 90. The screw bolts 92 have nuts 93 (Figure 2) which may be tightened up against the 35 flange 94 of head 24. The lower portion of the generator 15 which is cylindrical is embraced by a clamp band 95 having separated terminals 96 through which a bolt 97 passes to tighten the clamp band 95 on the 40 generator 15. The clamp band 95 is formed with a pair of eyes or sleeves 98 which rest on set collars 99 adjustably secured by their 45 set screws 100 on posts 101 rising from the base plate 102.

50 A combined ignition gas burner and pilot light assemblage is provided as follows: A gas chamber 103 has a depending inlet fitting 104 controlled by a gas cock 105 and adapted to receive a hose or other gas supply pipe 106. Rising from the chamber 103 and communicating with it are two gas pipes 107 each having an elbow 108 at the top carrying a forwardly disposed burner nozzle 109 formed with a row of jet orifices 110 in the 55 upper side at the top thereof. The flow of gas from the inlet fitting 104 to the chamber 103 is controlled by a valve 111 advantageously in the form of a threaded needle valve passing through the threaded stuffing box 112 manually operable to regulate the flow 60 of gas to the respective pipes 107. Leading laterally from the depending auxiliary chamber 113 integral with the chamber 103 below the valve 111 is a lateral nipple 114 with which by-pass gas pipes 115 are connected, the upper ends of said pipes 115 connecting with elbows 116. Leading forwardly from the elbows 116 through the burners 109 centrally therein are pilot light tubes 117 terminating forwardly of bracing partitions 118 in said burners 109 near the front ends. The chamber 103 at the under side is formed with air inlet openings 119 for the admission of air to said chamber to mix with the gas rising in the pipes 107 after the 65 manner of a Bunsen burner. The burners 109 rest slidably on hook-shaped lateral brackets 120 on atomizer head 24.

The arrangement of the burner assemblage is such that it may be moved forward 70 or back on the brackets 119 and through the front end of the head 24 to position the gas burners 109 with their forward ends adjacent the forward end of the combustion chamber 17 or in the rearward position in 75 said chamber.

The numeral 120 indicates a weight 173 to resist movement of lever 73 upon a predetermined pull when exerted on the element 77.

When the burner is in use steam will be generated in the steam generator 15 by the heat of the burner and will pass outward through pipe 18 to pipe 19 and to valve 20 where it divides to pass to gage 21, by pipe 43 to the water feed control device 36, and by pipe 23 to atomizer head 24. Steam passing into the head 24 is directed forwardly past valve 30 through nozzle 27 to burner nozzle 33 and to combustion chamber 17. 100 The action of the steam in passing from nozzle 27 will create a vacuum in port 84 and vacuum chamber 85 associated with oil inlet pipe 25, and thus by ejector action drawing the oil along with the steam to the burner 105 nozzle 33. The valve 82 when opened either by manual operation through the medium of lever 86, rod 79 and lever 80, or by thermostatic action on the element 77, will admit air in greater or less volume to the port 84 110 thus reducing the vacuum in chamber 85 and thereby reducing the feed of fuel from pipe 25 by the action of nozzle 27. In the absence of steam air under pressure from a hand pump and directed through pipe 32 115 will have the same effect as the steam in atomizing the fuel passing through nozzle 33. When the hand pump and air therefrom are utilized the flame at the burner 33 is manually ignited. When steam from the 120 nozzle 27 is utilized to atomize the oil, the gas burner and pilot light assemblage of Figures 9 to 11 is utilized to ignite the flame and produce an initial heat for starting the burner to generate the steam in generator 15. 130

I would state in conclusion that while the illustrated example constitutes a practical embodiment of my invention, I do not limit myself strictly to the exact details herein illustrated, since, manifestly, the same can be considerably varied without departure from the spirit of the invention as defined in the appended claims.

Having thus described my invention, I claim:

1. In a liquid fuel burner, a steam generator, a water feed means connected with said generator, a steam pipe leading from said generator, an atomizing head having a vacuum chamber, a fuel pipe connected with said vacuum chamber, a steam nozzle in said atomizer head and in communication with the said steam pipe from the generator, said steam nozzle positioned to draw liquid fuel from said vacuum chamber and fuel pipe by ejector action, a valve controlling the flow of steam through said steam nozzle, a control device for the water feed means, said control device having a chamber, a diaphragm dividing the chamber, a water inlet and a water outlet on the control device at one side of the diaphragm, said chamber of said control device, at the other side of the diaphragm, being connected with said steam pipe from the generator, a valve controlling the flow of water to said control device from the inlet, lifting means for said valve, said lifting means carried by the diaphragm and subject to the steam pressure, a spring acting on said diaphragm to balance the water pressure, means to manually actuate said valve lifting means to hold the valve open until sufficient steam pressure is developed, an air inlet leading into said vacuum chamber, an air admission valve in said air inlet, means to open said air valve and to close the valve controlling the steam nozzle, and manually operable means to open said air valve.
2. In a liquid fuel burner, an atomizing head, a burner nozzle at the front of said head, means to direct an atomizing fluid through said head, a vacuum chamber in said head, a fluid fuel pipe connected with said vacuum chamber, said head having a passage from said vacuum chamber to a point adjacent said means for directing an atomizing fluid, an air inlet leading to said passage, and an air admission valve in said air inlet, together with a lever operatively connected with said air inlet valve and for opening said valve, and manually operable means adapted to open said valve.
3. In a liquid fuel burner, a steam generator having a tubular steam chamber, the interior of said tubular steam chamber forming a combustion chamber, a burner nozzle in said combustion chamber, means to direct steam to said nozzle from said generator, means to direct oil to said nozzle at a point

to be atomized by the steam, and a gas burner and pilot light assemblage comprising a pair of gas burners disposed at opposite sides of said nozzle, a pilot light in each of said gas burners, and means slidably mounting said assemblage and permitting a forward and back movement of the gas burners and pilot lights in the combustion chamber.

4. In a liquid fuel burner, a burner nozzle, a tubular structure surrounding said burner nozzle, means forming a combustion chamber about said nozzle and in front of the same, a gas burner and pilot light assemblage comprising a pair of burners, the burners of a pair being disposed at the opposite sides of a nozzle, a pilot light in each gas burner longitudinally thereof, and means slidably mounting the gas burner assemblage and permitting forward and backward movement of the gas burners and pilot lights in said combustion chamber.

5. In a liquid fuel burner, a burner nozzle, a combustion chamber adjacent one end of which said nozzle is disposed, means to direct atomized fluid to said nozzle, gas burners disposed at opposite sides of said nozzle in said combustion chamber, pilot light pipes disposed longitudinally in said gas burners terminating near the front ends thereof, gas pipes leading to the respective gas burners, a fitting forming a gas chamber communicating with said gas pipes, bypass connections from said gas chamber to said pilot light pipes, and valve-controlled means to admit gas to said gas chamber.

6. In a liquid fuel burner, a burner nozzle, a combustion chamber adjacent one end of which said nozzle is disposed, means to direct atomized fluid to said nozzle, gas burners disposed at opposite sides of said nozzle in said combustion chamber, pilot light pipes disposed longitudinally in said gas burners and terminating near the front ends thereof, gas pipes leading to the respective gas burners, a fitting forming a gas chamber communicating with said gas pipes, bypass connections from said gas chamber to said pilot light pipes, and valve-controlled means to admit gas to said gas chamber; together with supporting means on which the gas burners are slidably supported for movement forward or back in the combustion chamber.

7. In a liquid fuel burner, a steam generator having a steam chamber thereon made tubular to form a combustion chamber, and means to clamp the generator to said atomizer head, said clamp means consisting of a frame fitting within the tubular steam chamber and composed of separate sections, an atomizer head and fastener screws passing through the frame at the joints between the sections and engaging said atomizer head.

8. In a liquid fuel burner, a burner noz-

zle, a fuel inlet pipe in communication with said nozzle to supply fuel thereto, and fuel supply means comprising a reservoir in communication with said pipe, said reservoir having an overflow outlet, an oil pan adapted to receive the oil from said overflow, a lever suspending said oil pan, an inlet leading to said reservoir, a valve controlling said

inlet, lift means for said valve, a lever adapted to actuate said lift means, a toe on said last-mentioned lever, and a toe on said first-mentioned lever and engaging the first-mentioned toe for rocking the last-mentioned lever and lifting the valve. 10

ACHILLE KAIS.
